PROCESS FOR COKING CARBONACEOUS MATERIAL

Charles H. Hughes, Glen Ridge, N. J., assignor to
 Hughes By-Product Coke Oven Corporation,
 New York, N. Y., a corporation of New York

Original application October 25, 1939, Serial No.
 301,172. Divided and this application March 1,
 1941, Serial No. 381,357

5 Claims. (Cl. 202—12)

The present invention relates to a process for coking carbonaceous material and, more particularly, to a process for coking coal.

As those skilled in the art know, in the earliest times coke was produced in mound-shaped Meilers similar to the old method of burning charcoal in heaps. The beehive oven was a modification of these except that it was built of brick instead of sod or clay, and the earliest record of coking coal in a regular oven is an English patent to St. John granted in 1620 for making coke in a beehive form of oven. Although a German chemist, Becher, received a patent in 1700 for recovering tar from coking coal, it appears that it was not until Clayton's discovery in 1737 that the formation of a combustible gas when coking coal was noticed. About the year 1767, a form of coke oven, producing coke and recovering some tar and ammonia, was constructed in Germany and was described as a dome-like fire clay retort. In 1781, an attempt appears to have been made to recover the by-products, and a patent to the Earl of Dundonald was issued, and in 1792 Murdoch experimented with making gas from coal in retorts. These efforts bore fruit, and twenty years later the streets of London were lighted by gas.

The earliest records of the rectangular, or retort, ovens show them in operation in Germany about 1830. They had open walls, pierced by horizontal and vertical flues, and the walls formed a rectangular space which contained the charge. In 1856, Knab is reported to have built a group of retort coke ovens to recover by-products and illuminating gas. These ovens had flues on the bottom only, but, of course, no regenerator or recuperator system was provided. Moreover, there was no attempt to furnish uniform heating to the oven sole, the fire or flame passing from a grate through a central flue and then returning through flues on both sides thereof. The following year, Appolt built his first ovens in the shape of vertical and, later, horizontal retorts, using his gas only for heating his oven through horizontal flues. This was about the earliest closed retort coke oven, utilizing the gas for its own heating. By 1861 the Coppee coke oven of Belgian invention was in use on the Continent, and in 1873-74 it was introduced into England. It had vertical flues and was of the non-recovery type.

About 1862 Carves of France introduced side flues in addition to the bottom flues of Knab. About 1880, Simon, an English inventor, improved the Carves oven very materially by adding

recuperating flues. This oven had the oven flues placed horizontally, the gas and air being first burned in sole flues located underneath the oven chamber, then passing up through a riser to the ovens and down through three horizontal flues in series. In the years 1881 to 1883, Seibel patented an oven having horizontal flues and having neither grates nor regenerators. It is apparent that oven designs up to this time were so uneconomical of gas used in heating the ovens, or the coals were so lean in gas, that grates for burning coal were built into the ovens and the gas was first admitted over these grates, the amount of coal being such as to supply the required additional heat.

The first ovens of the Otto type had been erected in Germany in 1881, and in the same year Huessner appropriated the Knab-Carves model and built a hundred ovens in Germany, thus establishing the industry on a sound basis in that country, although the quality of coke from these ovens was inferior. In these ovens the flues were horizontal. A very substantial improvement was made by Hoffman, who added the Siemens regenerator to the Otto coke oven and thus provided the first really efficient coke oven, generally referred to in the art as the Otto-Hoffman coke oven. In 1888 Festner, a German inventor, changed the Otto-Hoffman design by using horizontal instead of vertical flues and abandoning the Siemens regenerators, replacing the same with a Ponsard gas furnace. Hoffman cooperated with Festner, and this design was called a Festner-Hoffman oven, having horizontal flues and recuperators. In 1887, the Semet-Solvay oven came into notice, the first of them having no recuperators or regenerators. It appears that some of the principal features of Semet's design were the introduction of the division wall, the building of the oven flue system as a sleeve out of D-shaped tile, and the starting of the combustion at the top, or No. 1, flue, and, in general, providing a structure which was strong, easily heated and had a reservoir of heat in the division walls.

From the foregoing historical survey of the development of the coke oven art, it appears that all designs of ovens for coking coal sprang from four roots classified as follows:

1. The beehive oven, which was developed from the mound of charcoal burners.
2. The Coppee oven, with vertical flues in the oven walls, these ovens being built narrow, long and high.

3. The Knab broad oven, with flues underneath.

4. The Knab oven modified by Carves, with the oven flues horizontally in the side walls as well as underneath.

The high, narrow coke ovens of the prior art described in the foregoing had various important disadvantages. For instance, a recent standard type was usually of the order of about 45 feet in length, about 16 feet high, and about 17 inches in width, and, because of their height and narrowness, they had to be constructed and built in very large individual units, so that the original cost of installation was extremely high. Generally speaking, it was not possible either to build or to operate relatively small units of the conventional type at a low cost.

Besides these economic disadvantages, the use of a high, narrow oven was limited to certain coals or coal mixtures. Coals which expanded upon coking could only be used if mixed with shrinking coals, as otherwise the wear on the walls was too great, and the increasing pressure might have led to destruction of the ovens. Using a large percentage of shrinking coals, as necessarily became general practice, the coal shrank away from the heating walls, causing the formation between coke and wall of irregular gaps and crevices which acted as channels for the gases distilled from the coal. Due to the irregularity of these channels, heat could not be applied so as to produce a uniformly carbonized coke in a short coking period, regardless of the method of heating or control employed.

It is well known in the art that this channeling brought the rich gases into immediate contact with the highly heated refractory walls, producing two unfortunate results. First, the contact of the crude gases with some 1440 square feet of brick at the highest temperature in the oven caused the destruction of a part of the valuable by-products contained in the gases. Secondly, the gases acted as an insulator between the hot walls and the coking coal, preventing considerable heat from reaching the charge by conduction. Again, the gases, being much lower in temperature than the walls, took up considerable heat from them and thus prevented this amount of heat from reaching the core of the charge at all. Both of these effects resulted in greatly retarding the coking time and were diametrically opposed to the results desired, for it was, of course, the purpose of the operation to transfer heat from walls to coal charge as efficiently as possible and in the shortest time. Moreover, the heating of the gases had the undesirable effect of passing the gases to the by-product plant in a superheated state, necessitating larger condensing surfaces to cool them.

A further disadvantage of the high, narrow coke oven was that the width of the charge varied over the length of the oven, for practical reasons being smaller at the pusher end than at the coke discharge end. In order to provide for uniform coking throughout this constantly varying oven width, more gas had to be burned in the flues at the coke end of the oven, necessitating a difference in size of heating flues over the length of the oven. This required very accurate control of the fuel gas to the individual flues.

Under these conditions, it was difficult to control heating conditions in these ovens, the oven structure was intricate and expensive, resulting in high-cost coke, and the coke produced was primarily suitable only for metallurgical pur-

poses and not for domestic use. Subsequently, a broad rectangular sole-fired coke oven attempting to eliminate these disadvantages and to coke coal at a lower cost was developed, but other difficulties arose.

5. Essentially, this broad oven construction provided a rectangular sole-fired coke oven having a multiplicity of long, independent, parallel heating flues arranged side by side, each of said flues being directly connected at each end to two shallow, horizontal hair-pin regenerators below and parallel to and individual to each separate heating flue for alternately supplying heated air to the flues and receiving the heat of waste gases discharged therefrom. Each heating flue was provided with a burner or means for supplying rich fuel gas to both ends thereof. In this manner all of the flames burned in independent and isolated flues in the same direction and extended from one end toward the other end of the oven. Thus, each heating flue and its associated regenerators could be alternately operated, independently of adjoining heating flues and regenerators.

25. Although this type of broad oven could be built in relatively small units, the entire heating system and the so-called regenerators were fundamentally incorrect. The oven was designed for underfiring with rich coke oven gas only. The use of coke oven gas with preheated air gave a short and hot flame resulting in non-uniform heating of the long, straight, parallel and independent heating flues. An excessively high temperature occurred at each burner, producing danger points or hot spots. Moreover, the regenerators were so designed that the waste gas and incoming air always circulated in a horizontal direction which failed to give satisfactory and efficient results.

30. 40. In other words, by eliminating some of the disadvantages of prior ovens, the broad oven described introduced new difficulties which were in part much more serious than the former. Thus, the ends of the heating flues in said broad oven were overheated, causing overcooking and quick overheating of the construction material of the oven, while black spots, too cold for proper coking, developed in the centers of the flues. Clearly, it was practically impossible to obtain proper coking of the center mass except, and then to only a small extent, by overcooking the masses at the ends of the flues. Then, the space provided above and below the regenerators was inadequate for the gases to spread or mushroom out before going through the checkerbrick. Moreover, the regenerators, which were individual for each flue, were insufficient in size and could not function satisfactorily. The velocity of the gases in the heating flues was too slow and in the regenerator too high for proper heat transfer. Of course, not only did this non-uniform distribution of heat greatly decrease the over-all efficiency of these ovens, but, especially, the hot spots, developed in the operation of the oven, caused early deterioration of the building material and greatly increased the cost of operation and maintenance. Although these difficulties were well known in the art, and, from time to time, various suggestions and proposals were made to eliminate them, none of these suggestions and proposals, so far as I am aware, was completely satisfactory and successful on a practical and industrial scale.

75. 70. I have discovered that the outstanding prob-

Item may be solved in a simple and completely satisfactory manner.

It is an object of the present invention to provide a process for coking carbonaceous material which eliminates the aforementioned difficulties experienced in the operation of conventional broad coke ovens.

It is another object of this invention to provide a process of coking coals, tars and oils to produce a coke substance with burning characteristics different from those of coke produced heretofore by prior art processes.

It is a further object of the invention to provide a coking process which is easily adaptable to the coking of any carbonaceous material, such as coal, peat, tar, lignite, pitch, culm waste and other low grade coals, fuel oil, bunker oils and other petroleum products, and the like.

It is also an object of the invention to provide a coking process for coking a broad flat layer of coal to produce a coke of far greater suitability for domestic purposes than that produced in the high, narrow walls of the prior art.

The invention also provides a process for coking coal in a thin layer to permit the free flow of hot evolved gases whereby an open cell structure results.

The invention also provides a coking process wherein a flow of combustible gases at a temperature sufficient to coke carbonaceous material is directed in a single serpentine stream beneath said material and out of contact therewith, whereby hot spots and partly under-coking and partly overcoking the carbonaceous material are avoided and whereby substantially uniform coking of said material can be obtained.

Other and further objects and advantages of the invention will become apparent from the following description taken in conjunction with the accompanying drawings, in which:

Fig. 1 illustrates a top plan and a horizontal plan sectional view of four ovens embodying the principles of the present invention, taken on line 1—1 of Figs. 2 and 3;

Fig. 2 depicts a transverse vertical sectional view taken on line 2—2 of Fig. 1;

Fig. 3 shows a front elevational view of the ovens, taken on line 3—3 of Fig. 1;

Fig. 4 is a vertical longitudinal sectional view through the oven and regenerators taken on line 4—4 of Fig. 1;

Fig. 5 illustrates a front elevational view taken on line 5—5 of Fig. 1, depicting the arrangement of the closed valve boxes on the coke side of the oven battery;

Fig. 6 depicts a front elevational view taken on line 6—6 of Fig. 1 and showing the arrangement of the open valve boxes on the pusher side of the oven battery;

Figs. 7, 8, 9 and 10 show the details of the combination air and waste gas valve in a coke oven employing the process of the invention;

Fig. 11 is a flow diagram showing the direction of air, fuel gas and waste gas in a single reversal through the series heating flues, regenerators, valve boxes and chimney flues of an oven in accordance with the process of this invention; and

Fig. 12 is a vertical section through the special T and diaphragm assembly through which the volume of fuel gas to each burner is regulated.

Broadly stated, the present invention relates to a process for coking a broad flat layer of carbonaceous material in a coking chamber wherein it can be sealed against the admission of

air. A flow of combustion gases at a temperature sufficient to coke the carbonaceous material is directed in a serpentine stream beneath the sole of said chamber, and said flow is alternately reversed to provide substantially uniform coking of said carbonaceous material. The process can be satisfactorily carried out in a rectangular broad coke oven heated with an uneven number of sole flues, preferably five, interconnected in series and arranged to support and to heat the floor of the oven. Each oven can be operated independently of the adjoining ovens. These heating flues are connected by openings located at opposite ends with two sets of vertical regenerators located below and parallel to the heating flues and coke ovens. The two sets of vertical regenerators are alternately used to supply pre-heated air to opposite ends of the series flue heating system and to receive the hot waste products of combustion. These regenerators have spacious, chamber-like passages both above and below the checkerbrick, giving the gases an opportunity to spread or mushroom out before passing through and thus increasing the time of contact and affording more effective heat transfer. A combination air and waste gas box, equipped with the necessary valves, is provided on both the pusher and coke sides of each oven for the accurate control of the air entering the regenerator and in order to control the draft for each oven.

A coke oven suitable for carrying out the process of the invention will now be more fully described to those skilled in the art, reference being had to the accompanying drawings illustrating a preferred embodiment thereof. Similar reference characters denote corresponding parts throughout the various figures.

Referring, now, more specifically to Figs. 1 to 4, reference characters 1, 2, 3, 4 and 5 denote the heating flues arranged in horizontal position, running parallel to the length of the oven, and connected in series under the floor of the oven. The interconnected heating flues are provided with burning means, such as gas burners B—1, B—2, B—3 and B—4 which are supplied with fuel gas under a moderate and constant pressure through supply manifolds F—1 and F—2 (Fig. 4). The fuel gas is conducted through pipes G—1 and G—2 (Fig. 4) to burners B—1, B—2, B—3 and B—4 (Fig. 1), and the fuel gas is regulated through a special T and an orifice (Fig. 12). Below each oven are located two sets of regenerators R—1, R—2 and R—3, R—4, built of standard checker brick or special checker brick in the usual manner. Regenerators R—1 and R—2 are connected with series flue 5 and chimney flue C—1 by passages P—1 to P—8 inclusive. Regenerators R—3 and R—4 are connected with series flue 4 and chimney flue C—2 by passages P—9 to P—16, inclusive. The alternate flow of waste gas and air and the circulation through the heating flues, regenerators and waste gas flues are controlled by the reversing dampers in the valve boxes, as will be more fully explained hereinafter. (See Fig. 11.)

The valve boxes may be of any suitable design and appropriate construction, as those skilled in the art will readily understand. It is preferred, however, to use valve boxes of the type illustrated in Figs. 7 to 10. It is to be observed that the preferred form of valve box has a single housing A, preferably a suitable metal casting, as of a corrosion-resistant material, such as alloy cast iron of the chrome type or the chrome-nickel

type or the like. In the housing is mounted at the top thereof an air inlet damper or valve V-2 of rectangular shape, the face of which, V-21, is adapted to make a substantially air-tight contact with the seat V-22 of a rectangular port V-23 in the top of the box or housing. Slightly projecting shelves V-24 on each of two opposite sides of the opening V-23 just below seat V-22 provide a seat upon which removable air-regulating bars B can be placed. The valve V-2 is supported by a valve stem V-25 which is keyed to a rotatable shaft S-1. The shaft is held in position by a suitable sleeve mounting S-4 which is rigidly fastened to the housing.

Inside the housing of the valve box, a valve chest is formed, and within this valve chest is mounted a waste gas exit damper or valve D-2, the face D-21 of which is adapted to make a substantially air-tight contact with the seat D-22 of a port D-23 at the bottom of the box. This port forms the upper end of passage or duct P-16 which connects the valve chamber with chimney flue C-2. The valve D-2 is supported by valve stem D-25, which is keyed to a rotatable shaft S-2. This shaft is mounted in a suitable sleeve mounting S-5, which is rigidly fastened to valve box A, and the shaft extends through the side of and outside the box.

Keyed to one end of rotatable shaft S-1 is the fulcrum of a bell crank V-8. The bell crank has a straight arm which is connected by a suitable connection to a cable C which runs around the entire battery of ovens. The other arm of the bell crank is curved outward and over the edge of box A and at its end it connects with a vertical adjustable rod S-3. This rod comprises three parts: the upper part S-31 connecting at the upper end thereof with the bell crank and with its lower end threaded; a turnbuckle S-32 which is screwed onto the threaded end of S-31, and a lower part S-33 having either a swivel or a thread at its upper end adapted to coact with S-32 and connected at its lower end to a lever V-4. Lever V-4 is keyed to the end of shaft S-2 which protrudes from the side of the valve box. The turnbuckle is adjusted to make rod S-3 of such length that air valve V-2 is open when waste gas damper D-2 is tightly closed, and vice versa.

In passage P-16 there is a rectangular plate damper D-6 adapted to close off the passage in any degree required. It is mounted on a shaft S-6 which forms its longitudinal axis. This shaft extends the width of the passage, and one end of it passes through a side of the passage. The shaft is suitably mounted in the sides of passage P-16. To the end of shaft S-6 which protrudes from the side, a quadrant Q is attached.

The reversing mechanism for operating the air and waste gas dampers is not shown, as those skilled in the art are familiar with the construction and operation. It may be briefly described as consisting of a motor driven drum around which the endless cable C is wound. A time clock, which is set for fixed reversal periods, is adapted to make the necessary electrical contacts required for starting and stopping the motor and for shifting the gears which change the direction of travel of cable C. The cable is adapted for alternately opening and closing all dampers as required.

The same design of valve boxes, assembled right and left, as required, are used on both sides of the oven battery, and cable C, which extends

around the entire oven battery, is wound around the motor drum and is adapted to travel in opposite directions at each side of the battery. Thus, all air inlet valves or dampers on the pusher side of the battery are open, and all waste gas dampers are closed; during the same reversal period, the air valves on the discharge side are closed, and the waste gas dampers are open, thus completing the circulation through the heating system and regenerators. The opposite is true during the alternate reversal period.

The operation of this improved broad coke oven will now be described, particularly in conjunction with Fig. 11, which illustrates diagrammatically the flow of gases through the several flues, ducts, regenerators, dampers and valves, for the convenience of those skilled in the art.

Assuming that the regenerators R-1 and R-2 are being preheated by the outgoing gases of combustion, valve V-1 is closed and damper D-1 in passage P-8 is opened, permitting a flow of waste gas to chimney flue C-1. The air to be preheated enters through valve V-2, damper D-2 in passage P-16 being closed. The air flows into passage P-15, which is large enough to permit it to mushroom out, and then uniformly up through the hot checkerbrick in regenerator R-4 to passage P-14, whence by passages P-13 and P-12 the now partially heated air is brought to the spacious passage P-11 below regenerator R-3. The air then passes up through the checkerbrick in regenerator R-3. This checkerbrick is hotter than that in regenerator R-4, and the already heated air, on passing through, is brought to a very high temperature. It will be observed that provision of relatively large gas spaces above and below the regenerators permits the gas (here, air) to spread out before entering the checkerbrick and thus slows down its passage through the regenerators, giving improved heat transfer. The hot air passes along passage P-10 above regenerator R-3 and up passage P-9 to heating flue 1. This preheated air for the combustion of the fuel gas at the burners is delivered in flue 1 in great excess over the air requirements for burner B-1 and, after the combustion at burner B-1, the air, still in considerable excess of the requirements of the next burner in the series, passes mixed with the products of combustion to burner B-2, and similarly to all burners successively.

The hot waste gases of combustion pass out of the series flue heating system from flue 5 through passage P-1 to passage P-2, which is sufficiently large for the gases to spread uniformly, and then downward, relatively slowly, through regenerator R-1. The waste gases are very hot at this point and give up a great deal of their heat to the checkerbrick in regenerator R-1, becoming considerably cooler as they pass down into passage P-3 below the regenerator. The gases are then brought through passages P-4 and P-5 to the roomy passage P-6 above regenerator R-2, and thence go down at reduced velocity through the checkerbrick in regenerator R-2, to give up much of their remaining heat thereto and to emerge considerably cooler in passage P-7 below. These cooled combustion products flow through passage P-8 and damper D-1 into chimney flue C-1.

It is evident from the foregoing that, during the operation in the direction detailed in the paragraphs immediately preceding the present one, (i. e., air entering at valve V-2 and waste gases going to the stack through damper D-1 and chimney flue C-1), the draft set up is in the direction from heating flue 1, through flues 2, 3 and

4, to heating flue 5. Therefore the flame at burner B-1, located at the turn between flues 1 and 2 (see also Fig. 1), is deflected by the draft into flue 2. Similarly, the flames of burners B-2, B-3 and B-4 are deflected into flues 3, 4 and 5, respectively. Thus, with the draft in this direction, there is no flame in flue 1, and the flames are burning at the coke end (with respect to the oven) of flues 2 and 4 and at the pusher end of flues 3 and 5. The hottest end of flue 2—and this applies as well to flue 4—is under the coke end of the oven, and the flue gets progressively less heat from burner B-1 as one moves down toward the pusher end. Contrariwise, the hottest ends of flues 3 and 5 are those under the pusher end of the oven, while they get least heat from burners B-2 and B-4, respectively, at the ends under the coke end of the oven. It is obvious from this that flues 2 and 4 furnish most heat to the coke end of the oven on this run, somewhat less to the centre, and least to the pusher end, while flues 3 and 5 furnish most heat to the pusher end of the oven, somewhat less to the centre, and least to the coke end. Adding these two effects, the conclusion is arrived at that the sum of the heat furnished at any point along the length of the oven is about the same as at any other point, irrespective of the distance from the actual burners themselves.

Upon a reversal of the draft, accomplished as described supra, with the preheated air entering at the coke end (with respect to the oven above) of flue 5, the flames of burners B-4, B-3, B-2 and B-1 are deflected into flues 4, 3, 2 and 1, respectively. In this case, then, the flames burn at the pusher ends of flues 2 and 4 and at the coke ends of flues 1 and 3, so that the effect of each individual flue upon the oven is just opposite to that detailed in the foregoing paragraph. The cumulative or additive effect of the whole series of flues beneath the oven, however, is exactly the same as in the other case. In other words, the heat furnished throughout a full cycle is practically uniform for the entire oven length, so that, with no black spots possible at the centres of the flues, there can be neither overcooking at the ends of the oven nor undercooking at its centre. Moreover, the reversal of the flames, being deflected alternately from one flue into another, eliminates the danger of hot spots.

When the regenerators R-1 and R-2 are raised to the temperature necessary for preheating the air, the directions of flow of the air and the waste gases are reversed by opening damper D-2 and valve V-1 and closing damper D-1 and valve V-2. Air then enters through valve V-1 and, damper D-1 in passage P-8 being closed, flows through passage P-7 and upward through regenerators R-2 and R-1 in series, by means of the interconnecting passages P-6 to P-2, described supra. Passage P-1 then connects with heating flue 5. As detailed immediately above, the flames are then deflected by the draft into heating flues 4, 3, 2 and 1. The waste gases flow downward through regenerators R-3 and R-4 and through interconnecting passages P-9 to P-16 and so into chimney flue C-2.

The operation of the valve boxes is clear from Figs. 7 to 10. In the position shown, cable C has traveled to the left, moving the straight arm of bell crank V-8 in the same direction. The bell crank has turned shaft S-1 to which it is keyed. This movement of the shaft has raised air valve V-2 from its seat. The curved arm of bell crank V-8 has been moved downward in an arc and has pushed down upon adjustable rod

S-3, which has in turn depressed lever V-4. Lever V-4 has turned shaft S-2, to which it is keyed, and this in turn has lowered damper D-2 into its seat. The travel to the right of the cable reverses this order, opening damper D-2 and closing air valve V-2.

The open position of the air valves V-2 on the pusher side of the battery is illustrated by Fig. 6, which shows the cable as having traveled to the left. The arrangement of the damper boxes on the coke side at the same time is depicted in Fig. 5, air valves VI being closed.

Stack draft is used for drawing air into the regenerators and for removing the gases of combustion. The stack draft for each separate coke oven is regulated by the position of the plate damper D-6, which is held in position in the passage to the chimney flue by quadrants Q. The air valves are equipped with air-regulating bars B, as mentioned supra. Bars B are movable, and the volume of air to each regenerator is controlled by the size and number of removable bars used to regulate the size of the opening into the body of the box (see Fig. 10).

In the operation of the oven as an entire unit, oven doors W-1 and W-2 are closed and sealed air-tight, as may be seen from Fig. 4. Coal is charged through the charging holes H in the top of the oven (see also Figs. 1 and 2), and the cone-shaped piles are levelled off in the usual manner by levelling ram K, introduced through a small door in the pusher side oven door W-2 (see Figs. 4 and 6). The charging hole covers N are replaced and sealed air-tight. Fuel gas is then burned with preheated air in the flues underneath the coking chamber to provide a substantially uniform coking temperature for the entire area of the oven sole upon which the coal charge is supported. As is well known by those skilled in the art, the coking temperature varies depending upon whether low or high carbonization is desired. Thus, a suitable temperature for low coking, such as about 600 to about 700° C., to a suitable temperature for high coking, for instance, about 1150 to about 1450° C., can be successfully used. Reversal periods of suitable duration are employed, as those skilled in the art will know, and a reversal about every 15 minutes has been found to give satisfactory results. An off-take pipe M at the end of the oven provides an outlet for the gases evolved during coking, and these pass to the by-product plant. After the coal is coked, oven doors W-1 and W-2 are removed, and the coke is pushed in the customary way.

In providing gas for heating the ovens, the fuel gas, under a slight and constant pressure, is conducted through supply manifolds F-1 and F-2 and into risers G-1 and G-2 (see also Fig. 3). Its supply to the burners is regulated through a special T, conveniently located in each of the risers G-1 and G-2. This T, shown in Fig. 12, is so designed that, by removing plug T-1, the diaphragm T-2 can be replaced with one having a larger or smaller orifice, as required.

As noted supra in the structural description of the valve boxes, the air supply for each separate oven is regulated by the size and number of removable bars B (see Figs. 9 and 10) which are placed in the openings of the air valves at the two ends of the oven. This gives accurate air control at each oven and, together with the fuel gas control provided by means of the special T, permits independent and accurate con-

trol of the performance of each individual oven. This, with the other advantageous features described herein, gives my novel and improved process combination a flexibility of operation never before attained by the coke oven art.

It will also be appreciated that, according to my novel process, it is possible to produce a coke which is far more suitable for domestic purposes than was the coke produced by the processes employed in the high, narrow ovens of the prior art. The pressure in the plastic mass resulting from a deep, narrow charge materially affected the coke structure, so that a hard, dense, slow-burning coke having a close cell structure was necessarily produced. Such coke was really only suitable for metallurgical purposes, although the surplus was sold for domestic uses. Coke for domestic use should have an open, free-burning cell structure, and this type of coke can be made by my process. Leveling off the coal charge in an oven using my process over the entire horizontal heating surface gives a thin layer of about 10 to about 18 inches in depth spread evenly over a surface about 35 to about 45 feet long and about 8 to about 12 feet wide. The free flow of hot, evolved gases through the thin coal charge and the low pressure to which the coal in the plastic state is subjected create entirely different carbonizing conditions from those prevailing in the high, narrow ovens. An open cell structure results, and, in addition to the fact that a different molecular arrangement of the coke structure is developed, the carbonizing reaction is accompanied by less than the amount of cracking of by-products which resulted from contact with the hot, vertical surfaces of the prior art. Thus, the broad, flat oven herein described in connection with my improved process can be operated to leave a suitable volume of volatile matter in the coke to insure the free-burning properties desirable in domestic coke. It will, of course, be understood that an appropriate mixture of coals can as readily produce a high grade metallurgical coke by my novel process, so that my process has the great advantage of being adaptable to the production of either domestic or metallurgical coke.

Although the present invention has been disclosed in connection with a preferred oven construction for carrying out the same, variations and modifications of this construction may be resorted to by those skilled in the art, without departing from the principles of the invention. Thus, while a preferred arrangement of valves has been described and a preferred reversing mechanism for their operation has been indicated, those skilled in the coke oven art will readily perceive that other operative valvular means could be substituted for my arrangement and that other valve-actuating means could be used with satisfactory results. It will also be observed that, while I have preferred to employ a regenerative system under each oven which comprises two sets of vertical regenerators with each set comprising two regenerators connected in series, sets of one regenerator or of three or more series-connected regenerators could be satisfactorily used with relatively minor alterations and adjustments. Moreover, while I have described my invention particularly with reference to the coking of coal, it will be readily understood that it is as easily adaptable to the coking of any carbonaceous material, such as peat, tar, lignite, pitch, culm waste and other low grade coals, fuel oil, bunker oils and other petroleum products,

and the like. I consider all of these variations and modifications to be within the true spirit and scope of the present invention, as disclosed in the foregoing description and defined by the appended claims.

The present application is a division of my pending application Serial No. 301,172, filed October 25, 1939, and titled "Broad coke ovens," now Patent No. 2,234,171.

10 I claim:

1. The process of coking carbonaceous material in a coking chamber of a long rectangular oven broader than its height, which comprises introducing carbonaceous material into said coking chamber; spreading said carbonaceous material onto the sole of said coking chamber in a layer that is thinner than its width and length; sealing said oven against the admission of air; establishing under substantially the entire sole of said coking chamber and substantially parallel and immediately adjacent thereto a flow of hot combustion gases to furnish heat at a temperature sufficient to coke said carbonaceous material on the sole of said coking chamber; changing the direction of said flow of hot combustion gases at predetermined space intervals under the sole of said coking chamber to provide a single and continuous serpentine stream of hot combustion gases under substantially the total area of the sole of said coking chamber and in a plane substantially parallel to the sole of said coking chamber; alternately reversing the direction of said flow of hot combustion gases at predetermined time intervals to reverse the entire single and continuous serpentine stream of hot combustion gases, whereby uniform heating conditions over substantially the total area of the sole of said coking chamber can be attained and whereby hot spots and partly overcooking and partly undercooking the carbonaceous material on the sole of said coking chamber are avoided; and continuing said alternate reversals until the entire volume of the layer of carbonaceous material in said coking chamber is fully coked, whereby carbonaceous material is coked in said coking chamber substantially uniformly.
2. The process of coking carbonaceous material in a coking chamber of a long rectangular oven broader than its height, which comprises introducing carbonaceous material into said coking chamber; spreading said carbonaceous material onto the sole of said coking chamber in a layer that is thinner than its width and length; sealing said oven against the admission of air; establishing under the sole of said coking chamber a plurality of substantially parallel individual streams of preheated air having their ends at predetermined space intervals under the sole of said coking chamber; alternately changing the direction of flow of preheated air in said plurality of substantially parallel individual streams to provide substantially parallel individual streams wherein preheated air flows in opposite directions in adjacent streams; alternately merging the ends of adjacent individual streams to combine the flow of preheated combustion air in said plurality of substantially parallel individual streams of preheated combustion air into a single and continuous serpentine stream of preheated combustion air under substantially the total area of the sole of said coking chamber; introducing a fluid fuel at the merged ends of adjacent individual streams of preheated combustion air in said single and continuous serpentine stream of preheated combustion air, whereby the direction of

flow of preheated combustion air in said adjacent individual streams will determine the individual stream in which the fluid fuel will flow; burning said fluid fuel in said plurality of substantially parallel individual streams of preheated combustion air to propagate therewith a plurality of flames alternately traveling in opposite directions in said individual streams to furnish heat to the sole of said coking chamber at a temperature sufficient to coke the carbonaceous material thereon; alternately reversing the direction of flow of said preheated combustion air in said single and continuous serpentine stream of preheated combustion air to propagate the flames in the adjacent individual streams and in directions opposite to those prior to reversal, whereby uniform heating conditions over substantially the total area of the sole of said coking chamber can be attained, and whereby hot spots and partly overcoking and partly undercoking the carbonaceous material on the sole of said coking chamber are avoided; and continuing said alternate reversals until the entire volume of the layer of carbonaceous material in said coking chamber is fully coked, whereby carbonaceous material is coked in said coking chamber substantially uniformly.

3. The process of coking carbonaceous material in a coking chamber of a long rectangular oven broader than its height, which comprises introducing carbonaceous material into said coking chamber; spreading said carbonaceous material onto the sole of said coking chamber in a layer that is thinner than its width and length; sealing said oven against the admission of air; establishing under substantially the entire sole of said coking chamber and substantially parallel and immediately adjacent thereto a flow of hot combustion gases to furnish heat at a temperature sufficient to coke said carbonaceous material on the sole of said coking chamber in a plurality of substantially parallel individual streams in a plane substantially parallel to the sole of said coking chamber having their ends at predetermined space intervals under the sole of said coking chamber; merging the ends of said plurality of substantially parallel individual streams of hot combustion gases to form a single stream and to change the direction of flow of hot combustion gases; alternately reversing the direction of said flow of hot combustion gases at predetermined time intervals in said plurality of merged substantially parallel individual streams, whereby uniform heating conditions over substantially the total area of the sole of said coking chamber can be attained and whereby hot spots and partly overcoking and partly undercoking the carbonaceous material on the sole of said coking chamber are avoided; and continuing said alternate reversals until the entire volume of the layer of carbonaceous material on the sole of said coking chamber is fully coked, whereby carbonaceous material is coked substantially uniformly.

4. The process of coking carbonaceous material in a coking chamber of a long rectangular oven broader than its height, which comprises introducing carbonaceous material into said coking chamber; spreading said carbonaceous material onto the sole of the coking chamber in a layer that is thinner than its width and length; sealing said oven against the admission of air; establishing a single stream of combustion air in a narrow conduit; introducing said single stream of combustion air into a spacious chamber, thereby reducing the velocity of said single stream of

combustion air; passing said single stream of combustion air in a plurality of upward currents in contact with hot refractory surfaces to effect a transfer of heat from said hot refractory surfaces to said combustion air to preheat the same; merging said plurality of upward currents into another single stream; confining said single stream of preheated combustion air in another narrow conduit to increase the velocity thereof; passing said single stream of preheated combustion air under the sole of said coking chamber in a plurality of substantially parallel individual streams having their ends at predetermined space intervals under the sole of said coking chamber; alternately changing the direction of flow of preheated combustion air in said plurality of substantially parallel individual streams of preheated combustion air to provide substantially parallel individual streams wherein preheated combustion air flows in opposite directions in adjacent individual streams; alternately merging the ends of adjacent individual streams to combine the flow of preheated combustion air in said plurality of substantially parallel individual streams into a single and continuous serpentine stream of preheated combustion air under substantially the total area of the sole of said coking chamber; introducing a fluid fuel at the merged ends of adjacent individual streams of preheated combustion air in said single and continuous serpentine stream of preheated combustion air, whereby the direction of flow of preheated combustion air in said adjacent individual streams will determine the individual stream in which the fluid fuel will flow; burning said fluid fuel in said plurality of substantially parallel individual streams of preheated combustion air to propagate therewith a plurality of flames alternately traveling in opposite directions in said plurality of individual streams to furnish heat to the sole of said coking chamber at a temperature sufficient to coke the carbonaceous material thereon; alternately reversing the direction of flow of said preheated combustion air in said single and continuous serpentine stream of preheated combustion air of propagate the flames in the adjacent individual streams and in directions opposite to those prior to reversal, whereby uniform heating conditions over substantially the total area of the sole of said coking chamber can be attained, and whereby hot spots and partly overcoking and partly undercoking the carbonaceous material on the sole of said coking chamber are avoided; and continuing said alternate reversals until the entire volume of the layer of carbonaceous material in said coking chamber is fully coked, whereby carbonaceous material is coked in said coking chamber substantially uniformly.

5. The process of coking carbonaceous material in a coking chamber of a long rectangular oven broader than its height, which comprises introducing carbonaceous material into said coking chamber; spreading said carbonaceous material onto the sole of the coking chamber in a layer that is thinner than its width and length; sealing said oven against the admission of air; establishing a single stream of combustion air in a narrow conduit; introducing said single stream of combustion air into a spacious chamber, thereby reducing the velocity of said single stream of combustion air; passing said single stream of combustion air in a plurality of upward currents in contact with hot refractory surfaces to effect a transfer of heat from said hot refractory surfaces to said combustion air to pre-

heat the same; merging said plurality of upward currents into another single stream; confining said single stream of preheated combustion air in another narrow conduit to increase the velocity thereof; passing said single stream of preheated combustion air under the sole of said coking chamber in a plurality of substantially parallel individual streams having their ends at predetermined space intervals under the sole of said coking chamber; alternately changing the direction of flow of preheated combustion air in said plurality of substantially parallel individual streams of preheated combustion air to provide substantially parallel individual streams wherein preheated combustion air flows in opposite directions in adjacent individual streams; alternately merging the ends of adjacent individual streams to combine the flow of preheated combustion air in said plurality of substantially parallel individual streams into a single and continuous serpentine stream of preheated combustion air under substantially the total area of the sole of said coking chamber; introducing a fluid fuel at the merged ends of adjacent individual streams of preheated combustion air in said single and continuous serpentine stream of preheated combustion air, whereby the direction of flow of preheated combustion air in said adjacent individual streams will determine the individual stream in which the fluid fuel will flow; burning said fluid fuel in said plurality of substantially parallel individual streams of preheated combustion air to propagate therewith a plurality of flames alternately traveling in opposite directions in said plurality of individual streams to produce a single and continuous serpentine stream of combustion

35

products to furnish heat to the sole of said coking chamber at a temperature sufficient to coke the carbonaceous material thereon; introducing said stream of hot combustion products into another spacious chamber, thereby reducing the velocity thereof; passing said stream of hot combustion products in a plurality of downward currents in contact with refractory surfaces to effect a transfer of heat from said stream of hot combustion products to said refractory surfaces; merging said plurality of downward currents into another single stream; confining said single stream in another narrow conduit, thereby increasing the velocity thereof; passing said single stream to a waste gas stack; alternately reversing the direction of flow of said combustion air, said preheated combustion air, said preheated combustion air in said single and continuous serpentine stream beneath the sole of said coking chamber to propagate the flames in the adjacent individual streams and in directions opposite to those prior to reversal, whereby uniform heating conditions over substantially the total area of the sole of said coking chamber can be attained and whereby hot spots and partly overcoking and partly undercoking the carbonaceous material on the sole of said coking chamber are avoided, and alternately reversing the direction of flow of said hot combustion gases; and continuing said alternate reversals until the entire volume of the layer of carbonaceous material on the sole of said coking chamber is fully coked, whereby carbonaceous material is coked substantially uniformly.

CHARLES H. HUGHES.
